UNITED STATES PATENT OFFICE.

QUIMBY S. BACKUS, OF WINCHENDON, MASSACHUSETTS.

HEAT-RADIATING MANTEL.

SPECIFICATION forming part of Letters Patent No. 374,649, dated December 13, 1887.

Application filed November 9, 1886. Serial No. 218,421. (No model.)

To all whom it may concern:

Be it known that I, QUIMBY S. BACKUS, a citizen of the United States, residing at Winchendon, in the county of Worcester and State 5 of Massachusetts, have invented certain new and useful Improvements in Heat-Radiating Mantels; and I do hereby declare the following to be a full, clear, and exact description of the invention, such as will enable others skilled 10 in the art to which it appertains to make and use the same.

My invention is a mantel or fire-place front of such form and construction that it serves as a steam or hot-water radiator. Two forms 15 of the same are herein described, and the invention pointed out in the claims.

In the drawings, Figure 1 is a front elevation of one form of mantel embodying my invention. Fig. 2 is a vertical section of the 20 same on line $x-x$, Fig. 1. Fig. 3 is a section on line $y-y$, Fig. 1. Fig. 4 is a section on a like line of a modified form of my mantel. Fig. 5 is a transverse section of one side of 25 such form of mantel on line $z-z$, Fig. 4.

The same letters in the drawings indicate like parts.

I construct my mantel of four parts, A B C C', preferably of metal. Of these parts C C' constitute the sides or jambs of the mantel and 30 are placed at each side of the fire-place niche. The part B is placed above and upon these two parts and extends across the fire-place from one to the other. The part A is above this part B, and is provided ordinarily with a 35 mantel-shelf. The parts C C' are made with a chamber or receptacle, c, in each, and the part B is also hollowed or chambered. The chamber b within this latter part of the mantel is connected by pipes b' with the chambers

40 c in the jambs. When this mantel is used in connection with a steam-heating system, it is provided with an air-valve and with inlet and outlet 1 and 2. The fire-place can then be provided with a gas-log, which may be lighted to 45 imitate a grate-fire, the log affording the light and the mantel the grate part of the heat for the room. The mantel can in a similar manner be placed in a hot-water system.

I prefer, in most cases, to employ with my 50 mantel a water-heater or steam-generator, D, forming part of the gas-log or placed in

close proximity thereto. This water-heater or steam-generator is connected by pipes d' with the chamber b of the mantel, and is also connected by pipes d with the lower part of the 55 chamber c in the jambs. The water in the water back or log, on being heated, passes up through the pipes d into the chamber b and thence, as it cools, downward through the pipes b' to chambers c, then through pipes d' 60 into the log or back again, forming a complete circulation, in the course of which its heat is radiated or given off through the surface of the mantel to the air of the room.

It will be noticed that the construction with 55 the water-back or steam-generator is as well designed for use with a coal or other form of fire as with a gas log or burner. The part A is also of a hollow form, and the jambs below the chambers c are also hollow. These spaces 70 are not utilized in the construction just described; but in the modification shown in Fig. 4 I provide the front walls of these spaces with perforations, as shown at e. The rear of the jambs is provided with a shallow upward passage, E, which is continued upward and communicates with the space or chamber in the part A. The front wall of this passage is the rear wall of the chamber c and may be made corrugated, so as to provide additional heat- 75 ing-surface.

The cool air of the room passes in below the chambers c, then upward through the passage E, and is heated in its upward movement therethrough. It is then discharged into the 85 room through the part A and the openings in the front walls thereof. By this means all the heat of the water or steam in the mantel is fully utilized and there is little or no loss of heat.

The parts may be connected in any usual manner, and the form and connections of the heating-chambers of the mantel may be differently arranged and connected without departing from the spirit of my invention.

What I desire to claim and secure by Letters Patent is—

1. A mantel having chambers within the same, and steam or water inlets and outlets to said chambers, substantially as described.

2. A mantel consisting of hollow jambs on either side of the fire-place, a hollow part con-

necting the same above the fire-place communicating with the hollow jambs, and steam or water inlets, substantially as described.

3. The combination, with a hollow or chambered mantel, of a water-back communicating with said mantel, substantially as described.

4. The combination, with a hollow or chambered mantel, of a water-back communicating with said hollow or chambered mantel at two or more points at different elevations, substantially as described.

5. The combination, with a hollow or chambered mantel, of a water-back, pipes *d*, connecting the water-back with the mantel above the water-back, and pipes connecting the mantel with the water-back on a level with the latter, substantially as described.

15 6. A mantel consisting of the hollow parts

C C', the hollow part B, communicating with the parts C C', and the hollow part A, provided with a mantel-shelf, substantially as described.

7. The combination of the hollow parts A B C C', the said parts C C' being provided with chambers *c* and recesses below the same, and having openings through the front walls of said recesses, of the pipe E, connecting said recesses with the interior of A, said part A being provided with openings in the front wall of the same, substantially as described.

20 25 30 In testimony whereof I affix my signature in presence of two witnesses.

QUIMBY S. BACKUS.
